Thaddeus Barton

United States Patent Office.

GEORGE WILKINSON, OF PROVIDENCE, RHODE ISLAND, ASSIGNOR TO GORHAM MANUFACTURING COMPANY, OF SAME PLACE.

Design No. 3,924, dated March 22, 1870.

DESIGN FOR SPOONS AND FORKS.

The Schedule referred to in these Letters Patent and making part of the same.

To all whom it may concern:

Be it known that I, GEORGE WILKINSON, of the city and county of Providence and State of Rhode Island, have originated a new Design in articles of silver and plated ware for Spoons and Forks, called the "Lily," of which the accompanying photograph, with this specification, is a full and complete description, that is to say, the article of spoons and forks, substantially as shown in the said photograph.

Claim.

The design for spoons and forks, substantially as herein set forth.

GEO. WILKINSON.

Witnesses:

JOHN F. P. LAWTON,
THEODORE A. BARTON.
